**METHOD AND APPARATUS FOR DYEING
TEXTILE ARTICLES**

Friedrich R. Frenzel, Skogshyddan, Solna, Sweden
Filed May 23, 1958, Ser. No. 737,309
Claims priority, application Sweden May 25, 1957
6 Claims. (Cl. 8—150)

This invention relates to means for dyeing textile articles, such as hosiery, so that they are given areas of gradually varying colours.

Ladies' stockings are known, which are given a shade of colour by dyeing the back of the stocking up to the longitudinal middle line at the front thereof with a darker colour with a decreasing darkness towards said front middle line. The soft impression of the leg of the wearer of said stocking is however only apparent when the stocking is seen from the front, while when seen from behind the stocking is only dark and may even have the opposite effect by the increasing brightness toward the sides of the stocking.

The main object of the invention is to provide means by aid of which especially ladies' hosiery, but also bathing-suits, jumpers or similar articles of dress may advantageously be dyed so that they are given a shade of gradation of colour, which when the stocking is put on the leg gives the latter a more pronounced rounding.

A further object of the invention is to provide means by which the stockings or the like are dyed to give said stockings a soft impression seen from the front as well as from behind, by dyeing the stocking along opposite longitudinal side areas only with a varying for instance decreasing tone from the sides of the stocking.

Still another object of the invention is to provide means for dyeing the sides of the textile article to different extent, with different colour or darkness. A stocking may in this manner be coloured to correct knock-knees and bandy-legs respectively by differently dyeing the inner or outer side of the stocking. A bathing suit may in similar way be coloured to bring some parts of the body into stronger relief or making the same less apparent.

Another object of the invention is to provide a substantially inverted V- or U-shaped support structure or frame composed of two bars or boards on which the article is drawn and which cooperates with a member parallel with the said frame and adapted from outside to urge the fabric between said bars or the edges of said boards upwardly to give the article substantially an inverted V- or U-shape before immersing the same partially into a dyer's bath.

Still another object of the invention is to provide a support structure or frame by which stretching of the fabric is avoided. For this purpose said bars or boards of the frame are hinged together along a longitudinal axis of the frame so that said bars or boards will move towards each other when said intermediate outside member engages with the fabric to form said inverted V-shape.

Another object of the invention is to provide means for tilting the support structure around its longitudinal axis so that the article will be unsymmetrically immersed in the dyer's bath and one downwardly projecting edge of the inverted V-shape will dip deeper into the bath than the other with the result that one side of the stocking or the like will be dyed to a larger extent than the other.

Still another object of the invention is to provide for differently dyed areas by suitably shaping the bars or boards of the frame on which the article is drawn and said outside member.

The above and other objects and advantages will be apparent from the following description of some preferred embodiments shown on the accompanying drawing. In the drawing

2

FIGURE 1 is an elevational view, partly in vertical section, of an apparatus for dyeing stockings;

FIGURE 2 is a view similar to that in FIGURE 1 and showing the members in other position;

5 FIGURE 3 is a side elevational view of a support structure;

FIG. 4 is a schematic sectional view, taken on the line IV—IV of FIG. 1;

FIG. 5 is a schematic sectional view taken on the line V—V of FIG. 2;

FIG. 6 is a schematic sectional view taken on the line VI—VI of FIG. 3;

15 FIG. 7 is a schematic sectional view, similar to FIG. 4, but embodying a modification;

FIG. 8 is a schematic sectional view, similar to FIG. 7, but showing a second position corresponding to that of FIG. 5;

20 FIG. 9 is a schematic sectional view, similar to FIG. 4, but embodying a further modification;

FIG. 10 is a schematic sectional view, similar to FIG. 9, but showing a second position corresponding to that of FIG. 5, and taken on the line X—X of FIG. 11;

25 FIG. 11 is a fragmentary elevational view of the stocking form shown in FIGS. 9 and 10 with portions of the stocking broken away; and

FIG. 12 is a side elevational view, partly in section, as seen in direction XII—XII of FIG. 1.

The support structure or frame according to the invention is used for all around closed articles such as stockings, jumpers, bathing-suits, skirts or the like. Of course said articles include such that may temporarily be made closed. For sake of simplicity the following description is restricted to stockings as any other similar article may be treated in an analogous manner.

30 35 The apparatus according to FIGURES 1 and 2 for dyeing of articles of the type described comprises a trough 1 for a dyer's bath in or outside of which a pair of synchronously driven conveyor chains 2, 3 move preferably continuously. A support structure or frame 11 for a stocking 12 (see FIGS. 4—10) drawn on the same is pivotally mounted in a bracket 13 on the chain 2. A rearwardly projecting arm 14 of the frame 11 carries a roller 15 which runs against the underside of a guide bar 16 along the conveyor chain. Said guide bar 16 has an upper return portion with a guide 16" to prevent the stocking frame 11 from falling down during the return trip; and an upwardly bent portion at 16' permitting the support structure to be lowered into the bath during a suitable period of time as said roller passes said portion 50 55 60 65 70 75 80 85 90 95 100 105 110 115 120 125 130 135 140 145 150 155 160 165 170 175 8945 8950 8955 8960 8965 8970 8975 8980 8985 8990 8995 9000 9005 9010 9015 9020 9025 9030 9035 9040 9045 9050 9055 9060 9065 9070 9075 9080 9085 9090 9095 9100 9105 9110 9115 9120 9125 9130 9135 9140 9145 9150 9155 9160 9165 9170 9175 9180 9185 9190 9195 9200 9205

When the stocking is drawn on the frame it will take up a triangular cross section as shown in FIGURE 4 or a flat shape as shown in FIGURE 9. In dyeing condition said bar 21 is moved in between the bars 17 or boards 18 of the frame against the fabric as is shown in FIGURES 5 and 10 respectively so that turned over edge areas of the stocking project downwardly at 12'. When in this condition the stocking is slightly immersed into the dyer's bath only said downwardly projecting turned over areas will be dyed and at the subsequent suitably slow lifting of the stocking the colour will gradually increase from the undyed portion of the stocking to said edge areas so that an even change of colour is obtained.

It is to be noted that in the embodiments shown in FIGURES 5 and 10 the side parts 17 or 18 of the frame by pressing in the member 1 will move towards each other against a bias force and the stocking fabric will be subjected to little or no stretching.

A rigid frame is shown in FIGURES 7 and 8 and comprises a half cylindrical plate 22 having its open side turned downwardly towards the bath and as before an outside member 21 presses the underside of the stocking fabric into the concave space of said plate to form said V-shape.

To obtain varying degrees of dyeing on opposite sides of the article the frame is turnable about an axis substantially parallel with its length as is shown in FIGURES 3 and 6 where an adjustable pivot connection is inserted between the proper support structure 11 and the arm 14. The pivot connection comprises a stationary member 23 that has a central hole, and a pivot 23' which is frictionally engaged in the central hole.

The member 21 coacting with the frame 11 may be arranged in different ways although it is shown as a bar 21 (FIGS. 1 and 2) extending over the bath.

It is to be noted that the new means according to the invention may be carried out modified in different manners and that the described embodiments are given as examples only. Said means may be used in a continuously operating apparatus as well as for intermittent operation. Thus the support structure or frame may be made as units to be individually immersed into the dyer's bath and the member coacting with the support structure may be connected to said structure or separated from the same.

What I claim is:

1. A method for dyeing, with a liquid, opposite defined areas of a textile article of the type described, comprising the steps of drawing the textile article on an elongated structure including two spaced side portions, moving an elongated member parallel with said elongated structure and disposed between said side portions transversely to a plane through said side portions so as to engage the part of the textile article extending between said side portions to displace said part to an inverted V-shape, and applying the dyeing liquid to the legs of said V-shaped part.

2. A method for dyeing, in a bath, opposite defined areas of textile articles of the type described, comprising the steps of drawing the textile article on an elongated structure including two spaced side portions, deforming the textile article to an inverted V-shape with said side portions forming the legs of said V-shape, and immersing said textile article in its inverted V-shape into a bath to a predetermined depth with only the legs of said V-shaped part immersed into the bath.

3. In an apparatus for dyeing textile articles of the

type described, means operable for supporting the textile article for dyeing two opposite defined areas thereof comprising in combination, an elongated structure for drawing the textile article thereon, said elongated structure including two side parts hinged to each other to swing about a longitudinal axis, resilient means urging said side parts apart, and an elongated member parallel with the longitudinal side edges of said parts and movable in between the same transversely to a plane through said side edges and operable so as to engage the part of the textile article extending between said side edges to displace the same into a V-shape.

4. Apparatus for dyeing defined opposite areas of textile articles of the type described, comprising in combination, a receptacle for a dyeing bath, conveyor means running along said receptacle, an elongated structure for drawing the textile article thereon and having laterally spaced side portions forming a free area therebetween, said elongated structure being pivotally supported by said conveyor means and movable between an upper and a lower position, an elongated member supported by said conveyor means and extending horizontally over said receptacle and being disposed parallel with said elongated structure between the side portions thereof, at a predetermined level above the edges of said side portions in said lower position of the elongated structure.

5. In an apparatus for dyeing textile articles of the type described, means for supporting the textile article for dyeing two opposite defined areas thereof comprising in combination an elongated structure operable for drawing the textile article thereon, said elongated structure having two side portions spaced apart from each other and defining a free area therebetween, an elongated member parallel with said elongated member and disposed between said side portions and movable relative to said elongated structure transversely to a plane through said side portions, so as to engage the supported textile article extending between said side portions to displace it into a V-shape.

6. In an apparatus for dyeing textile articles of the type described, the arrangement of means for supporting the textile article for dyeing two opposite defined areas thereof, comprising in combination an elongated structure for drawing the textile articles thereon and having two side portions spaced apart from each other and defining a free area therebetween, a carrier for said elongated structure movable in a vertical plane between an upper and a lower position, means angularly adjustable about an axis parallel with said elongated structure for connecting the latter with said carrier, and an elongated member disposed parallel with said elongated structure between the side portions thereof and in a plane above the edges of said side portions of said elongated structure in its lower position.
